CLAIM

The ornamental design for a side load tray, as shown and described.

DESCRIPTION

FIG. 1 is a perspective view of a side load tray showing the new design;

FIG. 2 is a front view of the side load tray shown in FIG. 1; FIG. 3 is a rear view of the side load tray shown in FIG. 1;

FIG. 4 is a left side elevational view of the side load tray shown in FIG. 1 (the right side elevational view of the side load tray is a mirror image of the view shown in FIG. 4);

FIG. 5 is a top view of the side load tray shown in FIG. 1; and,

FIG. 6 is a bottom view of the side load tray shown in FIG. 1.
